SELF-CLEANING CLOTH BOARD FOR
AXMINSTER LOOMSClyde E. Brown, Grafton, Mass., assignor to
Crompton & Knowles Loom Works, Worcester,
Mass., a corporation of Massachusetts

Application December 16, 1939, Serial No. 309,638

9 Claims. (Cl. 139—7)

This invention relates to improvements in Axminster looms and it is the general object of the invention to provide a cloth board so constructed as to facilitate removal of lint which accumulates between the hooks of the nose or cloth board.

In Axminster looms having hooked or notched cloth boards for the reception of reed dents there is a tendency for lint to collect in the notches and interfere with the proper beating-up of the reed. In looms of the type set forth in Dacey and Robertson Patent No. 1,958,129 the cloth board has projecting therefrom a series of spaced hooks which assist in the tuft forming operation. The reed dents move forwardly between these hooks to a position slightly in advance of the front edge of the fabric retaining hook to beat the picks of filling over the hooks to a position in front of them. Lint collects in the slots between the hooks and becomes packed into masses sufficiently hard to bend the reed dents rearwardly to prevent the proper amount of motion of the reed. In the form of motion shown in the patent mentioned it is necessary from time to time to clean the lint from the cloth board by an operation which is not only expensive but also keeps the loom temporarily idle.

When the reed beats up it moves the fabric forwardly slightly with respect to the cloth board by an amount dependent among other things upon the thickness of the pick being beaten into the fell of the cloth. The latter therefore has a gradual forward feed along the cloth board and it is an important object of my present invention to form the cloth board in such a way as to enable the reed to push the accumulating lint upwardly against the under side of the cloth as the latter moves forwardly. In this way the cloth cooperates with the reed and the cloth board to remove lint by a forward motion from the spaces between the hooks.

It is another object of my present invention to provide a cloth board having forwardly and upwardly inclined surfaces between the hooks to form an acute angle pocket with the cloth into which the lint is pushed by the forward beat of the reed. As heretofore made the cloth board has been under-cut in such a way as to present a sharp angle to the bottom of the cloth tending to scrape off any lint on the underside of the fabric. With my improved cloth board the fabric moves over surfaces which form obtuse angles with the cloth board and there is little if any tendency for the blunt angles to scrape the underside of the cloth.

In the operation of an Axminster loom of the type to which my invention more particularly relates the forward beat of the lay pushes a shot of filling upwardly over the retaining hooks on spaced teeth of the cloth board, thereby temporarily raising the fabric being woven from the top surface of the cloth board. This lifting of the fabric is due to the forward motion of the reed which also acts to push the accumulated lint up the inclined surfaces, and it is a further object of my present invention to provide a cloth board so formed as to require a temporary lifting of the fabric to permit a space between the same and the cloth board into which the lint moving up the inclined surfaces can pass, subsequent forward motion of the cloth after the same is in its normal downward position on the cloth board dragging the lint forwardly away from the spaces between the slots.

With these and other objects in view which will appear as the description proceeds, my invention resides in the combination and arrangement of parts hereinafter described and set forth.

In the accompanying drawing, wherein a convenient embodiment of my invention is set forth:

Fig. 1 is a side elevation of a portion of an Axminster loom with certain parts in vertical section and showing the cloth board made according to the preferred form of my invention.

Fig. 2 is a plan view in the direction of arrow 2, Fig. 1.

Fig. 3 is a view similar to a portion of Fig. 1 with the reed in rear position and the needle laying a pick of filling in the warp shed.

Fig. 4 is a view similar to Fig. 3 but taken somewhat later in the loom cycle to show the reed in its forward position.

Fig. 5 is a view similar to Fig. 4 showing a modified form of cloth board more particularly adaptable to the yarn spacers shown in the previously mentioned patent to Lacey and Robertson.

Fig. 6 is a side elevation of the cloth board shown in Fig. 5, and

Fig. 7 is a rear elevation of the modified form of cloth board looking in the direction of arrow 7, Fig. 6.

Referring particularly to Figs. 1 and 2, the loom frame 10, front knife frame 11 and cutter blade 12, lay 13, reed 14 and separator blades 15 may all be of usual construction as shown for instance in the aforesaid patent. The blades 15 align with the reed dents 14 to define guideways for the tuft yarn Y extending from a tube frame 16, and brackets, one of which is shown

at 20 in Fig. 1, support a cross girt 21 to which is secured a cloth or nose board 22 extending across the loom. The cloth board is provided with slots 25 which define between them a series 5 of teeth 26 between which the dents 27 of the reed pass when the lay moves forwardly.

The operation of the loom is substantially the same as that set forth in the aforesaid patent, the lay moving backwardly and forwardly and 10 the binder warp B and B' separating to form a warp shed for the reception of a needle N which lays a double pick of filling F when the reed is rearward. The reed then moves forwardly to move the pick of filling up the forwardly and up- 15 wardly inclined rear surfaces 30 of the teeth 26 and over a hook lug 31 to a position in front of the latter. The pick of filling is indicated behind the hooks 31 in Fig. 3, while Fig. 4 shows the reed in forward position with the pick of filling 20 and forward edges 32 of the reed dents in front of the hooks 31. When the reed moves forwardly it forces the new filling against the fell of the fabric and gives a slight forward motion to the cloth C in the direction of arrow a, Fig. 4. The 25 take-up mechanism of the loom not shown also acts to move the cloth forwardly, or to the left as viewed in Fig. 4.

My invention relates more particularly to the shape of the bottoms of the slots 25. As shown 30 in the drawing the cloth board has an upwardly and forwardly inclined surface 40 located between adjacent teeth 26 and defining the bottom of the associated slot 25. The inclination of this surface 40 is such that it forms an acute 35 angle with the underside of the cloth C and its forward point, indicated at the left end of the slots as viewed in Fig. 1, lies substantially in advance of the fell of the cloth. Furthermore, the surface 40 forms an obtuse angle 41 with the 40 top surface 42 of the cloth board.

As already stated, continued operation of the loom results in an accumulation of lint designated generally at L in the slots 25, and successive forward beats of the lay packs this lint 45 into the spaces between the teeth 26. I find however that the mass of lint tends to move forwardly when it becomes sufficiently large to be engaged by the reed dents on the forward beat of the latter. The accumulated lint there- 50 fore receives repeated blows from the reed tending to move it up the inclined surface 40 and toward the fabric, with the result that part of the lint moves between the cloth and the upper surface 42 of the cloth board as indicated at 55 L' in Fig. 4. It is to be understood that the forward beat of the reed which exerts this forward thrust on the lint also causes a forward motion of the cloth and the latter drags that part of the lint designated at L' forwardly or 60 to the left out of the slots 25. The surface 40 extends rearwardly to a point as near the under surface 60 of the cloth board as is consistent with necessary strength of the cloth board. The vertical surface of the cloth board which 65 lies adjacent to the reed when the latter is in the position shown in Fig. 4 is very small with resultant negligible tendency on the part of the fibers to collect between the body of the cloth board and the reed dents.

70 The preferred form of the invention just described may be used in connection with any form of notched cloth board not necessarily depending upon the use of the guide plates 15. When the latter are used the arrangement can be as 75 set forth in Fig. 1, but if desired the modified

form of cloth board as shown in Figs. 5 to 7 can be used. In this form of the invention the teeth 59 extend downwardly as at 51 to define guides for the upper parts of the plates 15, thereby aiding in effecting alignment between the 5 guide plates 15 and the reed dents 27 in a manner similar to that described in the aforesaid patent to Dacey and Robertson. In order that the fibers may be free to fall away from the spaces between the hooks I extend a cut 52 10 lengthwise under the cloth board as indicated in Fig. 6, the breadth of this notch being insufficient to cause loss of registry between the separator plates 15 and the guide slots 25. The notch or groove 52 may extend downwardly from 15 a point immediately under the rear part of surface 40. The operation of the loom with my modified form of cloth board is as otherwise described in connection with the preferred form.

As a further feature of the operation of the 20 invention it is to be understood that forward motion of the reed moves the shot of filling up the hooks 31, thereby temporarily lifting the fabric from the top surface 42 of the cloth board. This lifting of the cloth is caused by the forward beat of the reed which serves also to push the accumulated lint up the inclined surfaces 40 and there is therefore temporarily provided a small space between the cloth and cloth board into which the lint can move. Subsequent dropping of the fabric pinches this portion of the 30 lint between the cloth and the cloth board, thereby assisting in moving the lint forwardly away from the slots 25.

From the foregoing it will be seen that I have 35 provided a cloth board so constructed that it cooperates with the reed and the cloth being woven to effect removal of lint accumulations between the teeth 26. It will further be seen that the surface 40 forms an acute angle with 40 the under side of the cloth which assists in dragging the matted fibers forwardly when the reed beats up to the position shown in Fig. 4. The blunt angle 41 has little or no tendency to scrape fibers from the bottom of the fabric being woven. 45 It will also be seen that in the modified form a portion of the depending guides for the plates 15 is removed to permit the fibers to fall of their own weight away from the cloth board.

Another feature of my invention is seen to 50 reside in the fact that the hooks 31 temporarily lift the fabric by the forward beat of the lay to provide a small space into which the reed can force a part of the lint, and that subsequent forward motion of the fabric after the same has 55 dropped to normal down position pinches this portion of the lint between the cloth and the cloth board and moves it away from the spaces between the teeth.

Having thus described my invention it will 60 be seen that changes and modifications may be made therein by those skilled in the art without departing from the spirit and scope of the invention and I do not wish to be limited to the details herein disclosed, but what I claim is: 65

1. In an Axminster loom having a reed with 70 dents and a cloth board over which the fabric being woven moves forwardly, said cloth board having a cloth supporting surface and spaced teeth between which the dents move when the reed beats forwardly and between which lint tends to collect, that improvement which consists of upwardly and forwardly inclined lint guiding surfaces formed on the cloth board in alignment with the reed dents and between the 75

- teeth and under the fabric and forming a pronounced acute angle with said cloth supporting surfaces, the reed dents when beating forwardly exerting a force on the lint between the teeth 5 tending to move said lint up the said guiding surfaces and into engagement with the fabric and the latter tending to move the lint forwardly due to forward motion thereof.
2. In an Axminster loom having a cloth board 10 over which the fabric being woven moves forwardly and said cloth board having a cloth supporting surface and spaced teeth to receive the dents of a reed when the latter beats forwardly and between which lint tends to collect, that improvement 15 consisting of upwardly and forwardly inclined lint guiding surfaces formed on the cloth board at the bottom of the spaces between the teeth and in alignment with the reed dents, the upper forward end of the guiding surfaces terminating adjacent to the under side of the fabric and forming a pronounced acute angle with said cloth supporting surface, forward movement of the reed dents in the spaces between the teeth tending to move lint in said spaces forwardly and 20 upwardly along said inclined guiding surfaces into engagement with the under side of the fabric and the latter tending by contact with the lint and forward motion thereof to move the lint away from the spaces between the teeth.
3. In an Axminster loom having a cloth board 25 over which the fabric being woven moves forwardly and said cloth board having a cloth supporting surface and spaced teeth to receive the dents of a reed when the latter beats forwardly and between which lint tends to collect, that improvement 30 consisting of upwardly and forwardly inclined lint guiding surfaces formed on the cloth board in alignment with the reed dents and at the bottom of the spaces between the teeth terminating adjacent to the under side of the fabric and forming a pronounced acute angle with the cloth supporting surface, the reed dents when moving forwardly in the spaces between the teeth tending to move accumulated lint in 35 said spaces upwardly and forwardly along said inclined guiding surfaces and into engagement with the under side of the fabric and the latter due to forward motion thereof and engagement 40 with the lint tending to move the latter away from the spaces between the teeth.
4. In an Axminster loom having a cloth board 45 over which the fabric being woven moves forwardly, said cloth board having a cloth supporting surface and spaced teeth between which lint tends to collect, the teeth having hooks extending above the top surface of the cloth board and the loom having reed dents which move forwardly between the teeth to positions in front of said hooks, the reed beating a shot of filling over said hooks and thereby temporarily raising the fabric from the top surface of the cloth board, that improvement which consists of forwardly and upwardly inclined lint guiding surfaces formed on the cloth board in alignment with the reed dents and defining the bottom of the spaces between the teeth and forming a pronounced acute angle with said cloth supporting surface, forward movement of the reed dents tending to move accumulated lint between said teeth up said inclined guiding surfaces into engagement with the under side of the fabric when the latter is temporarily raised from the cloth board and the fabric due to forward motion thereof and contact with the lint tending to move 55 the latter away from the spaces between said teeth.
5. In an Axminster loom having a cloth board over which the fabric being woven moves forwardly while normally in contact with the board, said cloth board having a cloth supporting surface and spaced teeth between which lint tends to collect, the teeth having hooks extending above the top surface of the cloth board and the loom having reed dents which move forwardly between the teeth to positions in front of said hooks, the reed beating a shot of filling over said hooks and thereby temporarily raising the fabric from the top surface of the cloth board, that improvement which consists of upwardly and forwardly inclined lint guiding surfaces formed on the cloth board between the teeth in alignment with the reed dents and defining the bottom of the spaces between said teeth and forming a pronounced acute angle with said cloth supporting surface, forward motion of the reed dents which temporarily lifts the fabric from the top surface of the cloth board exerting a force on the accumulated lint in said spaces tending to move the lint up the inclined guiding surfaces into the space between the temporarily raised fabric and that part of the cloth board in front of said inclined surfaces, the fabric due to forward motion thereof and contact with the lint between said fabric and the cloth board moving said lint away from the spaces while said fabric is in normal contact with the cloth board.
6. A cloth board to support the forwardly moving fabric of an Axminster loom which operates with a reed having dents, said cloth board having a cloth supporting surface and spaced teeth with reed dent receiving slots between said teeth, the bottoms of the slots being defined by upwardly and forwardly extending lint guiding surfaces to be in alignment with the reed dents when the cloth board is in the loom, the lint guiding surfaces leading to the top surface of the cloth board and forming a pronounced acute angle with the cloth supporting surface of the cloth board.
7. A cloth board to support the forwardly moving fabric of an Axminster loom which operates with a reed having dents, said cloth board having a cloth supporting surface and spaced teeth and reed dent receiving slots between said teeth, the bottoms of the slots being formed by upwardly and forwardly extending lint guiding surfaces to be in alignment with the reed dents when the cloth board is in the loom, the lint guiding surfaces leading to the top surface of the cloth board, said inclined surfaces forming pronounced acute angles with the cloth supporting surface of the cloth board.
8. A cloth board to support the forwardly moving fabric of an Axminster loom which operates with a reed having dents, said cloth board having a cloth supporting surface and spaced teeth and reed dent receiving slots between said teeth, the bottoms of the slots having lint guiding surfaces to be in alignment with the dents when the cloth board is in the loom, the lint guiding surfaces extending upwardly and forwardly to the cloth supporting surface of the cloth board and forming a pronounced acute angle with said cloth supporting surface, and said teeth having hooked portions extending above the cloth supporting surface of the cloth board.
9. A cloth board to support the forwardly moving fabric of an Axminster loom which operates with a reed having dents, said cloth board having a cloth supporting surface and spaced teeth

and reed dent receiving slots between said teeth, the bottoms of the slots having lint guiding surfaces to be in alignment with the reed dents when the cloth board is in the loom, the lint guiding surfaces extending upwardly and forwardly to the cloth supporting surface of the

cloth board, and said teeth having hooked portions extending above the cloth supporting surface of the cloth board and located behind the forward ends of the lint guiding surfaces.
